2 SHEETS—SHEET 2.

UNITED STATES PATENT OFFICE.

WILLIAM E. SHERBONDY, OF CLEVELAND, OHIO.

SUCTION-CLEANER.

1,238,449.

Specification of Letters Patent. Patented Aug. 28, 1917.

Application filed July 7, 1915. Serial No. 38,432.

To all whom it may concern:

Be it known that I, WILLIAM E. SHERBONDY, a citizen of the United States, residing at Cleveland, in the county of Cuyahoga and State of Ohio, have invented certain new and useful Improvements in Suction-Cleaners, of which the following is a specification.

This invention relates to carpet sweepers of that variety which may be designated as suction carpet sweepers, the object of the invention being to provide an improved apparatus of this character simple in construction, durable in use, easy to manipulate and which will effectively sweep a carpet and remove therefrom in an efficient way dirt, lint, threads and other debris, in short a very efficient and positively acting hand-operated device.

One of the objects of the invention is the provision of an improved apparatus of the character specified which may be used in a similar way to the ordinary carpet sweeper and yet do as effective cleaning as the ordinary portable electric suction sweeper, thus doing away with the use of a motor, which is expensive to operate as well as heavy and difficult to move around from room to room or floor to floor.

A further object of the invention is the provision of a suction sweeper having a wide mouth or inlet opening communicating with a rotary fan, which communicates in turn with a receptacle, such as a bag, for the reception of the dirt or debris, whereby the suction is created by an instrumentality located between the inlet opening or mouth and the dirt receiving receptacle, the organization being such that the fan is rotated through the medium of traction wheels at very great speed as compared with the movement of such traction wheels, whereby a large volume of air passes through the inlet opening or mouth, and in which the mouth or intake will be very close to the fan and the latter close to the opening in the receptacle for the dirt, thereby obviating the necessity of the dust and dirt being carried a long distance.

A further object of the invention is the provision of an improved suction sweeper in which the fan will be rotated through the medium of traction wheels on the movement of such traction wheels in one direction, as when the sweeper is moved forward, the energy imparted thereto being sufficient

during this movement to maintain the rotation of the fan at substantially the same speed during the return movement or the drawing backward of the sweeper.

The description following will present further improvements, it being understood that the various details may be more or less changed without departing from the spirit or scope of this improvement.

In the drawings accompanying and forming part of this specification, Figure 1 is a top view with the cover removed, of the present improvement; Fig. 2 is a cross-sectional view taken in line 2—2 Fig. 1; Fig. 3 is a detail view of the clutch by means of which the fan is rotated on the movement of the traction wheels in one direction; Fig. 4 illustrates the means for supporting and rotating the rotary brush located in the mouth of the sweeper, and Fig. 5 illustrates a detail of the bag.

Similar characters of reference indicate corresponding parts in the different figures of the drawings.

This improved suction sweeper comprises a simple casing 2 carrying the several working parts and to which a suitable handle is attached. A suitable receptacle, such as a bag, is also attached for the reception of the dirt and dust. This casing, in the preferred form shown, comprises three members readily separable from one another to permit access to the various parts, and in the present instance these three members comprise a main or intermediate chamber 5 carrying the fan and the gearing for rotating the same. This intermediate or main chamber 5 has generally a circular pan formation and may be readily cast in one piece of some suitable material, usually aluminum, it having an opening 6 at its underside which is in communication with an exhaust opening 7 at one side.

Secured to the underside of the part 5 of the casing is the inlet carrying member 8, having a disk formation adapted to close the opening 6 of the main casing member 5 and thus form a chamber for the rotary fan 9, the disk 10 of the casing member 8 having a circular opening 11 which communicates with and terminates in a wide, lengthwise extending opening or mouth 12, which in practice is about an inch and a half wide and about 8 inches long. The other member of the casing comprises a cover of pyramid form 13 secured to the top of the

casing member 5 for protecting the driving gearing from dust and dirt.

The casing at its rear has mounted thereon an axle 15 passing through suitable bearings 16 on the top of the casing member 5, and therefore above the fan and its chamber, and located on this axle at each end thereof is a traction wheel 17, preferably rubber tired. Located within the casing member 5 is a rotary fan 9 hereinbefore referred to, having curved blades 18 cut away at their inner ends adjacent to the axial opening 6 thereby to increase the communicating space between the inlet and the exhaust, which fan is mounted to rotate in a slightly oblique plane relative to the surface to be cleaned, it being located in the passage between the mouth 12 and the opening 7 which leads to the bag 19 for the reception of the dirt. This fan is mounted on an upright extending shaft 20, which is supported by suitable ball bearings 21 on the top wall of the casing 5 and carries a bevel pinion 22 in mesh with a bevel gear 23 located on a horizontally supported shaft 24 carried by suitable brackets 25 forming a part of the casing member 5. The opposite end of this horizontal shaft is provided with a pinion 26. The bevel gear and pinion located on this shaft are preferably formed of fiber, thereby to minimize any noise that may be present as the result of the meshing gears. This last pinion 26 is in mesh with a large gear 27 likewise suitably supported on the top of the casing member 5 and to the side of which gear is rigidly secured or formed as a part thereof a small pinion 28, which is in mesh with a large gear 29 connected with the traction wheel 17 in the manner about to be described, whereby on the movement of the traction wheel in one direction the train of gearing will rotate the fan at very high speed, causing a large volume of air to rush into the large mouth.

Located between one of the traction wheels 17 and the gear 29 is a suitable means for permitting the suction sweeper to be moved in one direction, as drawn backward, with the traction wheel 17 free of connection with the fan operating gear 29, the movement of the sweeper in the opposite direction giving sufficient momentum to the fan to cause it to rotate at substantially the same speed during the movement of the sweeper backward, and this means consists in the present instance of a suitable clutch comprising a circular band-formed casing 30 carried by the gear 29, which is loosely mounted on the traction axle 15 hereinbefore described, the traction wheels being fixed to the axle to rotate the same.

Fixed to the axle 15 and located within the band 30 is a circular disk 31 having cut-away portions 33, three in number, see

Fig. 3, for the reception of disks 34, whereby on the rotation of the traction wheels forwardly the disks loosely mounted in these cut-away portions will serve to lock the traction wheel with the gear and so rotate the fan through the train of gearing. On the movement of the traction wheels in the opposite direction the disks will play loosely in their cut-away portions and thus leave the traction wheels free of connection with the gear 29, while the fan will continue to operate owing to the momentum gathered during the movement of the sweeper in the other direction.

Located in the mouth 12 of the sweeper is a rotary brush 35 for facilitating the sweeping. The end walls of the mouth 12 are provided with enlarged openings 36 through which the ends of the brush shaft pass, such shaft having on each end thereof a pinion 37. The brush shaft is journaled in a pair of movable or shiftable plates 40, each pivotally supported at its forward end on the outer wall of the mouth 12, see Fig. 4, and each is provided with a slot 41 through which passes a pin or screw 42 for limiting the movement of the plate, and connected to each of the plates is a small spring 38 the opposite end of which is secured to the back wall of the mouth 12, these springs serving the purpose of returning one of the parts to normal position relative to the other in a manner which will be readily understood. Carried by each of the plates 40 is a rubber tired traction wheel 43 provided on its inner side with a pinion 44 in mesh with the pinion 37 hereinbefore referred to, whereby on the movement of these traction wheels the brush is rotated. These pivoted plates permit relative movement of the brush and mouth of the suction sweeper; that is to say, on the movement of the sweeper forward under pressure the traction wheels carried by the plates allow the mouth of the sweeper to move into closer engagement with the carpet or article to be swept, and on moving the sweeper backward, at which time the pressure exerted by the user on the device is withdrawn, the mouth is lifted somewhat from the article to be swept, thus facilitating the easier movement of the apparatus over the floor while bringing the mouth of the device into closer engagement with the carpet or article to be swept at a time when it is necessary that this be done.

Secured to the opening 7 by some suitable clamp, preferably of bayonet joint formation, as 39, is a suitable receptacle, preferably in the form of a bag 19, for the reception of the dirt which passes through the fan in a manner which will be readily understood. This bag is provided at its outer end, openable to remove the dust, with a suitable removable clamp 45, which, by means of a spring 130

46 or any other suitable means, may be secured to the shiftable stick or rod 47, which is provided with a forked end 48 attached to the main traction wheel axle and by 5 means of which the sweeper may be moved backward and forward over the floor by attaching the handle to the axle rather than to the casing the tipping of the casing or the forcing of the inlet too hard against the 10 floor is avoided.

The casing members 5 and 13 are each provided with parts 50 and 51 which when assembled will completely inclose the gearing.

15 From the foregoing it will be observed that in operation the revolving brush will serve to disturb the nap and assist in lifting the dust, dirt and lint and thus aid the suction created by the fan, so that such dirt 20 can be readily carried into the dust bag by the fan, and that, furthermore, the fan being of proper weight serves as a balance or fly wheel so that once it is put in motion it will maintain nearly the same speed with 25 very little effort exerted in the movement of the apparatus.

In a majority of the hand operated machines it has been found that if they are not pushed sufficiently hard or fast back and 30 forth over the floor the mechanism which must be used does not attain sufficient speed to perform its function. In the present improvement, however, very little effort is required to manipulate the device, and once 35 the fan commences to operate it maintains sufficient speed at all times to insure a sufficient velocity of the air to thoroughly and effectively clean, and it will be observed that on account of the very few moving 40 parts present the design of the apparatus may be very small and compact, so that it not only may be very economically produced, but can readily be operated under articles of furniture which are comparatively 45 near to the floor. Moreover, the fan may be very close to the floor, so that the dust and dirt can be easily picked up and carried the short distance through the machine, thereby overcoming any possible 50 chance of the machine becoming clogged, and this of course is greatly aided on account of the large opening of the intake or mouth and the large exhaust opening and by the comparatively large size of the fan, 55 which insures a large volume of air. In other words, by reason of the construction it will be observed that although the device itself is comparatively small the fan is comparatively large, the blades being quite high, 60 so that when it is running at normal speed a very large volume of air is moved. From the foregoing it will be observed that the shaft 15 is connected with the casing above the fan and its chamber, so that large traction 65 wheels may be used to support or sus-

pend the casing at the rear thereof and thus permit great speed to be imparted to the fan, while the front traction wheels are supported below the fan and its chamber, thus permitting the rear end of the 70 casing to be brought close to the floor and so incline such casing and its fan relatively to the floor as to obtain the advantages hereinbefore referred to.

In conclusion, it will be observed that I 75 have provided a very much simplified and effective suction sweeper readily and easily operated in the way in which an ordinary carpet sweeper is manipulated and yet obtaining results heretofore not always found 80 possible even with power driven portable apparatus.

I claim as my invention:

1. A manually operative suction sweeper comprising a casing inclined to a horizontal 85 plane and having a fan chamber extending from front to rear of the casing with the rear thereof closer to the floor than its front end, said casing having at the front thereof an inlet below the fan chamber and also 90 having an outlet adjacent to the fan chamber, a fan in said chamber of a size and weight to serve as a balance or fly wheel so that once the fan is put in motion it will be maintained at substantially the same speed 95 with very little effort exerted in the movement of the sweeper, an upright shaft to which the fan is secured, a pair of traction wheels connected with the casing, and gearing connecting said traction wheels with the 100 shaft for rotating the fan.

2. A manually operative suction sweeper comprising a casing inclined to a horizontal plane and having a fan chamber extending from front to rear of the casing with the 105 rear end thereof closer to the floor than its front end, said casing having at the front thereof an inlet below the fan chamber and also having an outlet adjacent to the fan chamber, a sweeping instrumentality located 110 adjacent to the inlet, a pair of traction wheels connected with the casing below the fan chamber and with the sweeping instrumentality for rotating it, a fan in the fan chamber of a size and weight to serve as a 115 balance or fly wheel so that once the sweeper is put in motion the fan will be maintained at substantially the same speed with very little effort exerted in the movement of the 120 sweeper, an upright shaft to which the fan is secured, an independent pair of traction wheels connected with the casing above the fan chamber, gearing connecting said traction wheels with the fan shaft for rotating the fan, and means for disconnecting the fan 125 and traction wheels during the movement of the sweeper in a backward direction whereby owing to the construction of the fan the rotation thereof will continue at substantially the same speed as during the 130

forward movement of the sweeper, the organization being such that the fan is driven at great speed as compared with the speed of rotation of the traction wheels.

- 5 3. A manually operative suction sweeper comprising a casing inclined to a horizontal plane and having a fan chamber extending from front to rear of the casing with the rear thereof closer to the floor than its 70 front end, said casing having at the front thereof an inlet below the fan chamber and also having an outlet adjacent to the fan chamber, a fan in said chamber of a size and weight to serve as a balance or fly 75 wheel so that once the fan is put in motion it will be maintained at substantially the same speed with very little effort exerted in the movement of the sweeper, an upright shaft to which the fan is secured, a pair 80 of traction wheels connected with the casing and having a diameter substantially coincident with the height of the casing, and gearing connecting said traction wheels with said fan, the ratio thereof as compared with 85 the traction wheels being such that the fan is driven with great speed as compared with the speed of rotation of the traction wheels.

4. A manually operated suction sweeper comprising a casing having an inlet and an 90 exhaust, means connected with the exhaust 95 for catching the dirt, a rotary sweeping instrumentality in said inlet, means for rotating it, a fan chamber of relatively large diameter as compared with the diameter and height of the casing, a large diameter light weight fan constructed to form a balance or fly wheel and to rotate at high speed in said fan chamber and of substantially the diameter of said fan chamber and having its 100 axis transverse to a horizontal plane, said fan being located in closer proximity at one side than at its other to the article to be cleaned thereby to bring it into closer relationship to the work to be done, the inlet 105 and exhaust communicating with the fan chamber through a relatively large uninterrupted opening, a pair of traction wheels connected with the casing, means for connecting the traction wheels with the fan 110 for rotating it at high speed as compared with the speed of the traction wheels, and means for disconnecting the fan from the traction wheels during the backward movement of the sweeper, the organization being such that without appreciable effort the fan 115 will be started and its rotation continued in the same direction at high speed for a considerable period of time notwithstanding the disconnection of its source of power therefrom.

5. A manually operated suction sweeper comprising a casing having an inlet and an exhaust for catching the dirt, a rotary sweeping instrumentality in said inlet, means for

rotating it, a fan chamber of relatively large diameter as compared with the diameter and height of the casing, a large diameter light weight fan constructed to form a balance or fly wheel and to rotate at high 70 speed in said fan chamber and of substantially the diameter of said fan chamber and having its axis transverse to a horizontal plane, said fan being located in closer proximity at one side than at its other to the article to be cleaned thereby to bring it into closer relationship to the work to be done, the fan comprising a disk having at its under side a plurality of relatively long downwardly extending curved veins, the inlet 75 and exhaust communicating with the fan chamber through a relatively large uninterrupted opening, a pair of traction wheels connected with the casing, means for connecting the traction wheels with the fan for 80 rotating it at high speed as compared with the speed of the traction wheels, and means for disconnecting the fan from the traction wheels during the backward movement of the sweeper, the organization being such that without appreciable effort the fan will be started and its rotation continued in the same direction at high speed for a considerable period of time notwithstanding the disconnection of its source of power therefrom. 85

6. A manually operated suction sweeper comprising a casing consisting of a bottom chamber having a relatively large intake mouth at its under side, a rotary sweeping instrumentality adjacent thereto, means for 100 rotating it, a fan chamber above said bottom chamber and communicating therewith by a relatively large axial opening and extending rearwardly of said bottom chamber and located with the rear thereof in substantially as close proximity to the surface to be cleaned as the bottom of the intake mouth and having a relatively large diameter compared with the diameter and height of the casing and provided with a relatively 105 large exhaust for the reception of means to receive the dirt, a fan in said fan chamber having a diameter substantially equal to the diameter of the fan chamber and extending rearwardly of the bottom chamber 110 with its axis transverse to a horizontal plane and constructed to serve as a balance or fly wheel so that once the fan is put in motion it will be maintained at nearly the same speed with very little effort exerted in the 115 movement of the sweeper, a shaft carrying said fan, a pair of traction wheels supported on the casing, gearing connecting said traction wheels with the fan shaft to rotate the fan at high speed as compared with the 120 speed of the traction wheels, and means for disconnecting the fan from the traction wheels during the backward movement of the sweeper and effective to permit the continued rotation of the fan at substantially 125 130

the same speed as that at which it rotates during the forward movement of the sweeper.

7. A manually operated suction sweeper comprising a casing having an inlet and an exhaust, dust collecting means connected to the exhaust, a rotary brush in the casing adjacent to the inlet, means for rotating the brush, a fan within the casing and having its axis transverse to a horizontal plane and of a size and weight to serve as a balance or fly wheel so that once the fan is put in motion it will be maintained at nearly the same speed with very little effort exerted in the movement of the sweeper, a shaft carrying the fan, traction wheels carried by the casing, gearing between the traction wheels and the fan shaft for rotating the fan at high speed as compared with the speed of rotation of the traction wheels and means for disconnecting the fan from the traction wheels during the backward movement of the sweeper, the organization being such that without appreciable effort the fan will be started and its rotation continued in the same direction at high speed for a considerable period of time notwithstanding the disconnection of its source of power therefrom.

8. A manually operated suction sweeper comprising a casing having an inlet and an exhaust, dust collecting means connected to the exhaust, a rotary brush in the casing adjacent to the inlet, means for rotating the brush, a fan within the casing and having its axis transverse to a horizontal plane and of a size and weight to serve as a balance or fly wheel so that once the fan is put in motion it will be maintained at nearly the same speed with very little effort exerted in the movement of the apparatus, a shaft carrying the fan, traction wheels carried by the casing, gearing between the traction wheels and the fan shaft for rotating the fan at high speed as compared with the speed of rotation of the traction wheels, and means for disconnecting the fan from the traction wheels during the backward movement of the sweeper, the organization being such that without appreciable effort the fan will be started and its rotation continued in the same direction at high speed for a considerable period of time notwithstanding the disconnection of its source of power therefrom, said fly wheel fan comprising a disk having at its under side a plurality of curved and downwardly projecting wide veins cut away at their inner ends to provide an increased space centrally of the fan in direct communication with the inlet.

9. A manually operated suction sweeper comprising a casing consisting of a bottom chamber having a relatively large intake mouth at its under side, a rotary sweeping instrumentality adjacent to said mouth,

means for rotating it, a fan chamber above the bottom chamber and communicating therewith by a relatively large axial opening and extending rearwardly of the bottom chamber and located with the rear thereof in substantially as close proximity to the surface to be cleaned as the bottom of the intake mouth and having a relatively large diameter as compared with the diameter and height of the casing and provided with a relatively large exhaust adapted to receive dust collecting means, a cover chamber above the fan chamber, a fan in said fan chamber and constructed to serve as a balance or fly wheel so that it may be easily and quickly put in motion and once in motion be maintained at nearly the same speed with very little effort exerted in the movement of the sweeper, said fan having its axis located transverse to a horizontal plane, an upright shaft carrying said fan and extending into the cover chamber, a pair of traction wheels supported on the casing, gearing located partly in the cover chamber above the fan for connecting said traction wheels and upright shaft to rotate the fan at high speed as compared with the speed of the traction wheels, and means for disconnecting the fan from the traction wheels during the backward movement of the sweeper.

10. A manually operated suction sweeper comprising a casing having a wide intake opening and an exhaust opening, a fan chamber therebetween and located in an inclined plane relatively to the floor, a fan in said chamber, traction wheels for supporting said casing, driving gearing between said traction wheels and said fan for rotating the latter, a rotary brush located in said intake opening, traction wheels in connection with said brush for rotating it, and means connecting said last traction wheels with the casing adjacent to the intake opening whereby the casing may be shifted relatively to said traction wheels and into closer relationship with the floor.

11. A manually operated suction sweeper comprising a casing having three superimposed chambers, one a bottom chamber having an intake opening in proximity to the floor, an intermediate chamber above said bottom chamber and inclined relatively to a horizontal plane and having at one side an exhaust, a rotary fan supported in said intermediate chamber with its axis transverse to a horizontal plane, a cover chamber above said fan chamber, an upright shaft extending from the fan into said cover chamber, a bevel gear thereon, a horizontal shaft supported by said casing, a bevel gear on said shaft meshing with said first bevel gear, traction wheels for supporting said casing, a horizontal traction wheel shaft carrying said wheels, and intermeshing gears between said pair of horizontal shafts.

12. A suction sweeper comprising a casing having an intake opening, plates pivotally secured to the outer side walls of said opening whereby said plates and casing have relative movement, a brush within said opening and journaled in said plates, traction wheels carried by said plates and connected with said brush for rotating the same, and resilient means connecting the plates with the casing.
13. A suction sweeper comprising a casing having an intake opening, plates pivotally secured to the outer side walls of said opening whereby said plates and casing have relative movement, a brush within said opening and journaled in said plates, traction wheels carried by said plates and connected with said brush for rotating the same, resilient means connecting the plates with the casing, and a stop for limiting the relative movement of the casing and plates.
14. A suction sweeper comprising a casing having a mouth provided with slotted end walls, a brush having a shaft projecting through said slotted end walls, a pair of plates pivotally connected to the end walls and in which said shaft is journaled whereby the plates and casing have relative movement, traction wheels carried by the plates and connected with the brush for rotating

the same, a spring connecting the plates with the casing, the pivotal connection of the plates with the casing being at the front side of the brush shaft and the spring connection being at the rear side thereof.

35

15. A manually operated suction sweeper comprising a casing consisting of a bottom chamber having at its under side an inlet mouth, a cover chamber and therebetween a fan chamber communicating with the bottom chamber and having an exhaust, a rotary fan in the fan chamber, an upright shaft carrying the fan and extending into the cover chamber, a pair of parallelly located shafts, one extending crosswise of the casing through the cover chamber and the other extending into the cover chamber toward the upright shaft, a pair of traction wheels carried by the first shaft, a stub shaft carried by the casing, gearing carried by said shafts for imparting movement from the traction wheels to the fan, and means connected with the traction wheels for disconnecting the fan therefrom on the backward movement of the sweeper.
